UNITED STATES PATENT OFFICE

DAVID M. WENGER, OF LEOLA, PENNSYLVANIA

WASHING MACHINE

Application filed April 27, 1929. Serial No. 358,713.

The invention forming the subject matter of this application is an improvement on the type of washing machine disclosed in my United States Patent No. 1,444,993, February 13, 1923.

The main object of the invention is to improve generally the structural details of the machine, and to render the several parts thereof readily detachable from each other and accessible for replacement or repair.

The main improvement over my prior construction resides in mounting the washing receptacle so that it may be brought to rest without stopping the motor controlling the rotation thereof, and may even be removed from its supporting bearings while the motor is in operation.

I have also improved the internal construction of the washing receptacle in order to add to the efficiency of its operation, and have formed the closures for the opposite ends of this receptacle in such manner that they may be snapped into locked position thereon without the necessity of turning them into exact predetermined position relative to the circumference of the open end of the said receptacle.

The invention consists in the combination and in the several subcombinations and details of structure more specifically set forth in the ensuing description, illustrated in the accompanying drawings and defined in the appended claims.

In the accompanying drawings, in which like reference characters indicate like parts throughout the several views.

Fig. 1 is a central vertical section through the washing receptacle part of the machine, with the supporting structure for the receptacle shown in elevation;

Fig. 2 is a plan view of the machine with part of the supporting standards broken away;

Fig. 3 is a perspective view of a controller forming part of this invention;

Fig. 4 is a perspective view of one of a series of ribs forming part of the internal construction of the washing receptacle;

Fig. 5 is a perspective view of a slightly modified form of rib constituting one of an-

other series of ribs forming part of the internal construction of the washing receptacle;

Fig. 6 is a horizontal section on the line 6—6 of Fig. 1, the details of construction of the washing receptacle being omitted for 55 clearness of illustration;

Fig. 7 is a horizontal section on the line 6—6 of Fig. 1, but with the parts shown in a different position;

Fig. 8 is a horizontal section on the line 6—6 of Fig. 1, with the parts thereof shown in a different position from those shown in Figs. 6 and 7;

Fig. 9 is a fragmentary vertical section through the controller illustrated in Fig. 3;

Fig. 10 is a vertical cross-section taken on the line 10—10 of Fig. 9;

Fig. 11 is a perspective view of one of the clutch elements forming part of the controller mechanism shown in Fig. 9;

Fig. 12 is a perspective view of one of the trunnion bearings for rotatably supporting the washing receptacle;

Fig. 13 is a perspective view of one of the trunnions which seats rotatably in one of the bearings and rotatably supports the washing receptacle;

Fig. 14 is a perspective view of one of the trunnion elements;

Fig. 15 is a vertical section taken on the line 15—15 of Fig. 6;

Fig. 16 is a vertical section taken on the line 16—16 of Fig. 6.

As shown in Fig. 1 of the drawings, the washing receptacle designated generally, by the reference character 1 is mounted for rotation about a transverse axis in a rectangular supporting structure 2, which may be constructed of angle irons or any other suitable material in any desired form.

A washing receptacle comprises a cylindrical body 3, formed of any suitable non-corrosive sheet metal, and provided with perforations 4 to permit the washing fluid contained in a tub (not shown) to circulate through said perforations into and through the interior of the washing receptacle for cleansing material placed therein. A circular partition 5 extends across the center of the body 3 and is secured to said body by the an-

nular clamping plates 6 and 7, of L-shaped cross-section, of which the vertical part thereof may be suitably riveted to the body portion. The partition 5 may be riveted or otherwise secured to the horizontal part of the clamping plates 6 and 7.

The cups 8 and 9 are cylindrical and are riveted to the partition 5 concentrically with the body 3, in order to form devices for squeezing the material being washed during certain positions of the washing receptacle in the rotation thereof. Also secured to the body of the receptacle at diametrically opposite parts thereof are the ribs 10, each of which is provided with lugs 11, 12 and 13.

Four of these ribs are employed in each receptacle, and all of them radiate from the center thereof, and each of these ribs is suitably secured to the body 3 and to the partition 5 by rivets or other suitable securing means.

These ribs 10 extend along the body 3 right down to partition 5, and the plates 6 and 7 are split to contact with the opposite sides of the ribs and to permit the said ribs to have their lower edge seated properly on partition 5.

Four other ribs 14 are secured to the body 3 and the partition 5 and on opposite sides thereof on a diameter at right angles to the plane of the ribs 10. The ribs 14 differ somewhat in construction from the ribs 10, as they are provided with flanges 15 and 16 extending from opposite sides of the rear vertical edge of said ribs. Lugs 17 extend laterally from the bottom edges of the ribs 14, and are

apertured to receive rivets or other suitable securing means for fastening the ribs 14 to the partition 5. The flanges 15 and 16 are also apertured to receive suitable rivets or other securing means for fastening the ribs 14 to the cylindrical body 3.

The corner of each of the ribs 14 is provided with recesses 17 and 18 to permit each rib to seat against the wall 3 and the partition 5 and extend over the flanges of the clamping plates 6 and 7. This construction is to provide for a very stiff and strong foundation to receive trunnions 19 and 20 riveted or otherwise suitably secured to the upright flanges of the plates 6 and 7 through the body 3 of the washing receptacle.

The trunnions 19 and 20 are somewhat similar in construction, and each of them comprises an arcuate plate 21 provided with apertures 22 at the corners thereof adapted to receive the rivets or other securing means for fastening the plate 21 to the body 3 and the clamping plates 6 and 7. A cylindrical trunnion 23 extends perpendicularly from the plate 21; and at the center thereof is provided with a stud 24 (see Fig. 13), having clutch cams 25 and 26 extending from diametrically opposite sides thereof.

The stud 24 is cylindrical, and the central bore 27 thereof has its axis alined with the diameter of the partition 5. This bore 27

forms a bearing adapted to receive rotatably the end 28 of the driving shaft 29 (see Figs. 6 and 14).

Bearings 30 and 31 for the trunnions 19 and 20, respectively, are suitably secured to upright members 32 and 33, respectively, forming part of the supporting structure 2 and arranged in suitable position to provide for rotation of the washing receptacle 1 in the tub with which this machine is ordinarily supplied.

The mechanism for supporting and rotating the washing receptacle 1 is designed to be moved to three distinct positions. In the first position, the receptacle may be seated by its trunnions 19 and 20 in the trunnion bearings 30 and 31, and may be freely removed from said bearings, even while the driving shaft 29 is in rotation; in the second position, the said mechanism may be manipulated so as to lock the washing receptacle rotatably in its trunnions, and at the same time be free from rotation by the driving shaft 29; in the last position the mechanism is positioned so as not only to lock the washing receptacle 1 rotatably in its trunnion bearings 30 and 31, but also to lock one of the said trunnions to the driving shaft 29, in order to impart the rotation of the said shaft 29 to the washing receptacle 1 as a whole.

On the right hand side of the machine as shown in Figs. 1 and 2, and on the side opposite to the trunnion bearing 30, there is mounted a gear box 34 which is suitably secured by a flange 35 to the upright member 32, which is provided with a cup-like receptacle 36 suitably secured to said upright member to form a positioning seat for the flange of the gear box 34.

The cup-like receptacle 36 is provided with a boss 37 against which is seated the boss 38 of a bevelled gear 39 which is secured to the shaft 29 to be rotated thereby by means of a pin 40. A driving pinion 41 extends from the drive shaft 42, which is journaled in a bearing 43 (see Figure 1) at substantially right angles to the shaft 29, and which has the end thereof provided with a tongue 44 adapted to be connected to any suitable fitting 115 for rotation by a motor or other source of rotary power.

On the other side of the supporting member 32 the drive shaft 29 has keyed thereon a sleeve 45 which is provided at its outer end with a flange 46 and has a disk 47 secured to one end thereof by means of screws 48. A ring 49 of a diameter permitting it to slide freely on the flange 46, is provided with an inturned flange 50 having an internal diameter slightly greater than that of the sleeve 45 in order to permit it to slide freely on said sleeve. The two flanges 46 and 50 are normally held in contact with each other by means of a coil spring 51 surrounding the 130

sleeve 45, and having one end thereof abutting against the flange 50, while the other end abuts against the disk 47.

It will be noted (see Fig. 12) that the 5 trunnion bearing 30 is secured to the upright member 32 by means of lugs 52 to the upright member 32. The receptacle 1 is shown in Fig. 6 in the position relative to the driving and supporting mechanism in which it may 10 be inserted in and removed from the bearings 30 and 31, regardless of whether the driving shaft 29 is rotating or not. As shown in Figure 7, the trunnion bearing 30 has the upper part of its outer end cut away to form a ledge 15 54, and as shown in Figure 12 the trunnion bearing 31 is composed of a semi-cylindrical support 56 surrounding the lower portion of a sleeve 55 and projecting through said sleeve so as to form a ledge 53. The ledge 53 forms 20 a vertical shoulder and the ledge 54 forms a similar shoulder 56; and the distance between these shoulders is very slightly greater than the distance between the ends 57 and 58 of the trunnions 19 and 20.

25 The left hand side of the machine as shown in Fig. 6 is provided with a clutch box 59 secured by bolts or other suitable fastening means 60 to the upright member 33. A boss 61 extends outwardly from the structure 33 30 and inside of the clutch box 59 to form a bearing for a thrust rod 62 which is adapted to slide in the said bearing toward and from the trunnion 20. A clutch disk 63 is secured to the thrust rod 62 by a pin 64, and a coil 35 spring 64' is interposed between the flat face 65 of this clutch disk 63 and the inner face of the clutch box 59 around the boss 61 thereof. In order to prevent rotation of the clutch disk 63 and the rod 62 keyed thereto, the disk 63 40 is provided with a lug 66 having a groove 67 formed therein to slide along a tongue 68 formed on the inner wall of the clutch box 59.

The rod 62 and the clutch disk 63 are thus 45 slidably but not rotatably mounted in the clutch box 59. In order to slide the rod 62 inwardly toward the trunnion 20, the outer edge of the clutch box 59 is provided with a flange 69; and on this flange is seated a cover 70 for the clutch box having a flange 71 50 formed thereon and adapted to fit snugly into the inner periphery of the clutch box 59.

The cover 70 (see Fig. 10) is provided with a lug 72 which seats in a notch 73 formed in the flange 69 to provide correct position of 55 the cover on said flange. The cover is securely bolted to the flange 69 by means of the bolts 74.

The cover 70 is centrally apertured and is 60 provided with a stud shaft 75 axially aligned with the rod 62. On the inner face of the cover 70 there is mounted rotatably, a clutch plate 76 provided with cam faces cooperating with similar cam faces on the disk 63. The clutch plate 76 is keyed to the stub shaft 75; 65 and on the outer end of the shaft 75 there is

secured a handle member 77 designed to rotate the stub shaft 75 and the plate 76 along with it. Diametrically opposite to the handle 77, and integral therewith, is a stop member 78 which is rotatable over an arcuate plate 79 (see Fig. 3). The ends of the arcuate plate 79 are provided with upturned projections 80 and 81, which form limiting stops engageable with opposite sides of the member 78 to stop the handle 77 in predetermined positions of 75 rotary adjustment.

The stop member 78 (see Fig. 6) is bored to receive a compression spring 82 which abuts at one end against the bottom of the boring in the member 78 and at its other end contact with a ball 83 in order to force the ball into frictional contact with the arcuate plate 79. This plate is provided with three little counter-sinks, of which only those designated by the reference characters 84 and 85 are shown; and these countersinks are adapted to receive and seat the ball 83 in order to lock the handle 77 in position predetermined by the location of the said countersinks.

As shown in Fig. 3, the handle 77 has three 90 definite positions, and these positions are indicated by the words "Remove," "Stop" and "Start". When the handle is in the position designated by the word "Remove" the trunnions 19 and 20 and the clutch mechanisms on each side of the receptacle 1 are in the position shown in Fig. 6. As will be apparent from Fig. 6, which is a horizontal cross-section, the receptacle 1 may be lifted 95 bodily from the trunnion bearings 30 and 31; because, in this case, the rod 62 and the driving shaft 29 are out of engagement with the bore 27 of the stud 24, and the recesses formed above the ledges 53 and 54 are specifically provided to permit the removal of the trunnions 100 19 and 20 bodily from the trunnion bearings 30 and 31.

On the opposite side of the supporting structure 33, the rod 62 has secured thereto by 105 means of a pin 86, a sleeve 87, which is adapted to be moved with said rod 62 into contact with the cylindrical stud 24. The end of the rod 62 projects from the face of the sleeve 87, a distance slightly less than the depth of the bore 27 formed in the stud 24. By this construction, it will be apparent from Fig. 7, that this projecting end 88 of the rod 62 will 110 seat in the bore 27 and prevent removal of the trunnion 20 from the trunnion bearing 31. The clutch plate 76 and the clutch disk 63 are provided with cooperating inclined cam faces 89 and 90 of any well known construction; and, as will be apparent from Figs. 7 and 8, the rotation of the stub shaft 75 by 115 means of the handle 77 will cause rotation of the clutch plate 76 over the clutch disk 63, and by sliding movement of the cam faces relatively to one another will push the thrust rod 62 to the right, as shown in Figs. 6, 7 and 8.

130

The clutch plate 76 is provided with flat parts 91 and 92 (see Fig. 11) adapted to cooperate with similar parts formed on the clutch disk 63 to lock the said disk and plate in the position shown in Fig. 8 with their cam faces out of contact with each other, in order to avoid any likelihood of stopping of the machine because of the thrust of the spring 64', effecting, through the inclined cam faces, movement of the thrust rod toward the left, to the position shown in Fig. 6, and thereby cause accidental disconnection of the receptacle from the driving shaft 29.

The clutch cams 25 and 26 of the trunnions 19 and 20 are provided with inclined cam faces 93 and 94 adapted to contact with correspondingly inclined cam faces 96 and 96', Figure 14 formed in the recess 95 of the sleeve 45.

It is to be understood, of course, that the clutch elements of the trunnions 19 and 20 are adapted to be used only when one or the other of said trunnions is seated in the trunnion bearing 30, the two trunnions being made identical in order that the receptacle 1 may be seated in its trunnion bearing without the necessity of determining which of the trunnions was provided with cam faces, adapted to cooperate with those formed in the sleeve 45. In other words, the receptacle is reversible, so far as the rotary mounting thereof is concerned, in its trunnion bearings 30 and 31.

The sleeve 87 on the thrust rod 62 is adapted, when said rod is moved to the right as shown in Figs. 7 and 8, to form a thrust bearing for the trunnion 20 or 19, as the case may be, and also form a base or seat on which the periphery of the stud 24 may rotate.

It will be obvious from Figs. 6, 7 and 8 that when the receptacle is seated in the trunnion bearings 30 and 31 as shown in Fig. 6, the said receptacle may be lifted bodily out of said bearings, whether the drive shaft be rotating or not.

The position of the several parts, as shown in Fig. 6, corresponds to the position of the handle 77 as indicated by the legend "Remove" on the face of the clutch box. When the handle 77 is moved into the position shown in Fig. 3, and indicated by the legend "Stop", the thrust rod is moved by the sliding of the inclined face 89 over the inclined face 90 toward the right, as shown in Fig. 7. This movement brings the sleeve 87 into contact with the stud 24 and moves the end 88, of the rod 62, into rotary locking engagement with the bore 27 of the stud 24. At the same time the pressure of sleeve 87 moves the receptacle 1 bodily toward the right and causes the outer periphery of the trunnion 19 to slide under the closed part of the trunnion bearing 30, and thereby to lock the trunnion 19 against removal from the trunnion bearing 30. The yielding resistance of the ring 49 holds the

stud of the trunnion 20 firmly against the sleeve 87 on the thrust rod 62.

In the position shown in Fig. 7, it is evident that the trunnion 20 could be lifted bodily from the trunnion bearing 31 if the projecting end 88 of the thrust rod 62 were not seated in the bore 27. However, the trunnion 19 has been moved beyond the recess 55, and is completely encircled by the bearing 30, so as to prevent removal thereof. It will be seen however, that the clutch elements 93 and 94 of the trunnion 19 are still out of engagement with the corresponding elements in the recess 95 of the sleeve 45. It will thus be apparent that while the washing receptacle is locked against removal from its trunnion bearings 30 and 31, it is not yet in driven contact with the driving shaft 29, and can be rotated manually to any desired position.

Further rotation of the handle 77 from the "Stop" position to the position indicated in Fig. 3 by the legend "Start", thrusts the receptacle 1 still further to the right and causes the clutch faces of the trunnion 19 to engage the corresponding clutch elements in the sleeve 45, and thereby locks the receptacle 1 to the driving shaft 29 to be rotated thereby. This final position is illustrated in Fig. 8, in which it will be seen that the outer cylindrical shell of the trunnion 19 has moved the flanged ring 49 inwardly against the resistance of the spring 51, and that the projecting end of the driving shaft 29 has entered the bore 27 of the stud 24. In this position, too, the thrust rod 62 has been moved to the limit of its movement by the cooperating engagement of the clutch disk 63 and the clutch plate 76, with the flat parts 91 and 92 of the disk 63 in supporting contact with the corresponding flat parts on the clutch plate 76.

A cylindrical vacuum cup 118 is fixedly secured in the closure plate 98 and concentrically therewith. The vacuum cup extends downwardly toward the ribs 10 and 14 and has the edge thereof closely adjacent to the corners of said ribs when the closure is securely fastened to the body 3 of the washing receptacle 1.

The closure plates are adapted to fit either end of the washing receptacle; and the vacuum cups carried thereby serve to suck the dirt from the clothing being washed in the receptacle, as the latter is rotated on its trunnion. The ribs 10 and 14 have a squeezing action on the clothing as it falls toward the center cup 8 or 9; and these ribs are perforated to permit the free circulation of cleansing fluid therethrough. The center partition 5 is also perforated on each side of the ribs 10 and 14 and outside of the cups 8 and 9. The cylindrical body 3 is also perforated so as to permit the free circulation of cleansing fluid therethrough as the receptacle is rotated in the tub, not shown.

What I claim is:

1. A washing machine comprising a support, oppositely disposed alined cylindrical bearings fixed to said support, a cylindrical receptacle having alined diametrically opposite trunnions extending from the opposite sides of said receptacle and rotatably mounted in said bearings, means extending into one of said bearings and engageable with one of said trunnions to cause rotation of the receptacle in said bearings, yielding means in said bearings to prevent driving connection of said rotation causing means with said trunnion, and means engageable with the other trunnion to move the first named trunnion into driven connection with the said rotation causing means.
2. A washing machine comprising a support, oppositely disposed alined cylindrical bearings fixed to said support, a cylindrical receptacle having alined diametrically opposite trunnions extending from the side of said receptacle and rotatably mounted in said bearings, a drive shaft extending into one of said bearings, cooperating clutch elements secured to one of said trunnions and to said drive shaft, means for holding said clutch elements normally separated from each other, and means for shifting said receptacle axially to effect engagement between said clutch elements and thereby cause rotation of said receptacle on its bearings.
3. A washing machine comprising a support, oppositely disposed alined cylindrical bearings fixed to said support, a cylindrical receptacle having alined diametrically opposite trunnions extending from the side of said receptacle and rotatably mounted in said bearings, a drive shaft extending coaxially with said trunnions into one of said bearings, a thrust rod slidable coaxially in the other of said bearings, yielding means in the first named bearing to hold the trunnion supported thereby out of engagement with said drive shaft, a clutch coupling between said drive shaft and said trunnion and means for moving said thrust rod against the other trunnion to force said receptacle and the first named trunnion into driven connection with the said drive shaft.
4. A washing machine comprising a support, oppositely disposed alined cylindrical bearings fixed to said support, a cylindrical receptacle having alined diametrically opposite trunnions extending from the side of said receptacle and rotatably mounted in said bearings, a drive shaft extending coaxially with said trunnions into one of said bearings, a thrust rod slidable coaxially in the other of said bearings and against the trunnion supported thereby, means for moving said thrust rod to and from any one of three predetermined positions in said other bearing, and means for yieldingly resisting the movement of said receptacle toward said

drive shaft, the receptacle being freely removable from its bearings when the thrust rod is in one of its three predetermined positions and being locked against removal from said bearings when the thrust rod is in its intermediate predetermined position and in driven connection with said drive shaft only when the thrust rod is in its third predetermined position.

5. A support, oppositely disposed cylindrical bearings fixed to said support, a receptacle, trunnions extending from said receptacle and slidably rotatably in said bearings, a drive shaft extending into one of said bearings, a clutch coupling for connecting said drive shaft and receptacle within said bearing, means for normally holding said receptacle out of driven contact with said drive shaft, and means slidable through the other of said bearings against the trunnion mounted therein to move said receptacle and its other trunnion into driven engagement with said drive shaft.

6. A support, oppositely disposed cylindrical bearings fixed to said support, a receptacle, diametrically opposite trunnions extending from said receptacle and slidable and rotatable in said bearings and removable therefrom, each of said trunnions being provided with cam clutch elements, a drive shaft extending into one of said bearings and having clutch elements engageable with the clutch elements of either of said trunnions when the receptacle is reversed in direction, a thrust rod slidable through the other of said bearings into and out of thrust contact with the other of said trunnions, a cam disk secured to said thrust rod, a casing coaxial with said bearings and fixed to said support, means on said cam disk and said casing to prevent rotation of said disk and thrust rod, and means rotatable on said casing and provided with a cam plate engageable with said cam disk to slide the thrust rod into engagement with the adjacent trunnion to move the clutch elements on the other trunnion into engagement with the clutch elements on the shaft.

7. A support, oppositely disposed cylindrical bearings fixed to said support, a receptacle, axially alined trunnions extending from said receptacle slidably and rotatably mounted in said bearings and removable therefrom, a drive shaft extending through one of said trunnions into one of said bearings, cooperating clutch elements on one of said trunnions and on said drive shaft, means for normally holding said clutch elements out of engagement with each other, rectilinearly slidable means engageable with the other of said trunnions to move the receptacle into driven engagement with said drive shaft, and means rotatable on said support to move said rectilinearly slidable means into engagement with said other trunnion.

8. A support, oppositely disposed cylind-

drical bearings fixed to said support, a receptacle, axially alined trunnions extending from said receptacle slidably and rotatably mounted in said bearings and removable therefrom, a drive shaft extending through one of said trunnions into one of said bearings, cooperating clutch elements on one of said trunnions and on said drive shaft, means for normally holding said clutch elements out of engagement with each other, rectilinearly slidable means engageable with the other of said trunnions to move the receptacle into driven engagement with said drive shaft, yielding means for normally holding said slidable means out of engagement with the adjacent trunnion, and means rotatable on said support to move said rectilinearly slidable means into engagement with the said adjacent trunnion and to move the receptacle 20 with the other trunnion into driven engagement with said drive shaft.

9. A support, oppositely alined bearings fixed to said support, a drive shaft extending into one of said bearings, a removable receptacle having trunnions slidably and rotatably mounted in said bearings, means for moving said receptacle toward said drive shaft and to a predetermined position in its bearings to lock the receptacle in said bearings but out of operative engagement with said drive shaft and to another predetermined position for locking the receptacle against removal from its bearings and in driven engagement with said drive shaft, and means for indicating when the receptacle is in any of its said predetermined positions.

10. A washing machine including a supporting frame, a cylindrical receptacle having a central partition between the ends thereof, trunnions extending in diametrically opposite alinement from the side of said receptacle, bearings fixed to said framework and in which said trunnions are rotatably mounted, means extending through one of said bearings and engaging one of said trunnions to rotate the receptacle, and closures detachably connected to the ends of said receptacle.

11. A washing machine including an open ended cylindrical receptacle having a substantially circular partition between the ends thereof, a compression cup secured to said partition concentric with the axis of said receptacle, ribs extending radially from the periphery of said cup to the wall of said receptacle and terminating a short distance below an end of said receptacle, a closure detachably connected to the open end of said receptacle, and a vacuum cup secured to the inside of said closure and having the edge thereof closely adjacent to the edges of said ribs.

12. A washing machine including an open ended cylindrical receptacle having a substantially circular partition between the ends

thereof, a compression cup secured to said partition at the center thereof, a closure detachably connected to an open end of said cylinder, and a cylindrical vacuum cup centrally secured to the inside of said closure 70 and extending toward the compression cup at the center of said partition.

13. A washing machine including an open ended cylindrical receptacle having a circular partition secured to the body of said receptacle between the open ends thereof, closures detachably connected to each of said open ends, cylindrical pressure cups coaxial with said body and secured to said partition with their open ends extending in opposite 75 directions, and cylindrical vacuum cups secured to said closures coaxially with the body of said receptacle and having their open ends extending towards the said partition.

14. A washing machine comprising an open ended cylindrical receptacle having a circular partition secured to the body of said receptacle between the open ends thereof, closures detachably connected to each of said open ends, cylindrical pressure cups coaxial 90 with said body and secured to said partition with their open ends extending in opposite directions, cylindrical vacuum cups secured to said closures coaxially with the body of said receptacle and having their open ends 95 extending toward the said partition, and ribs secured to said partition and the body of said receptacle and extending radially from the periphery of the pressure cups and vertically toward the vacuum cup to terminate a short 100 distance from the rims of said vacuum cups.

In testimony whereof I affix my signature.
DAVID M. WENGER.
